UNITED STATES PATENT OFFICE

HUBERT LANG, OF CHICAGO, ILLINOIS, ASSIGNOR TO GOSS PRINTING PRESS COMPANY,
A CORPORATION OF ILLINOIS

WEB ROLL SUPPORTING AND CONTROLLING MECHANISM

Application filed April 22, 1929. Serial No. 357,096.

The invention relates to new and useful improvements in web roll mechanisms and more particularly to means for handling and supporting web rolls, including vari-width rolls, for registering the rolls and for governing the feeding of the drawn-off webs, and finds a broad field of usefulness in rapid rotary printing presses and other web-using machines, which employ heavy web rolls and 10 run at high speeds.

Objects and advantages of the invention will be set forth in part hereinafter and in part will be obvious herefrom, or may be learned by practice with the invention, the 15 same being realized and attained by means of the instrumentalities and combinations pointed out in the appended claims.

The invention consists in the novel parts, construction, arrangements, combinations and 20 improvements herein shown and described.

The accompanying drawings, referred to herein and constituting a part hereof, illustrate one embodiment of the invention, and together with the description, serve to 25 explain the principles of the invention.

Of the drawings:

Fig. 1 is a fragmentary elevation, with parts broken away, of a mechanism embodying the invention;

Fig. 2 is a vertical longitudinal section of the mechanism, taken on line 2—2 of Fig. 3;

Fig. 3 is an elevation, and partial section through a web roll, taken on the line 3—3 of Fig. 1;

Fig. 4 is a vertical section taken on the line line 4—4 of Fig. 1;

Fig. 5 is a fragmentary vertical section taken on the line 5—5 of Fig. 1;

Fig. 6 is a fragmentary vertical section taken on the line 6—6 of Fig. 1; and

Fig. 7 is a fragmentary section taken on the line 7—7 of Fig. 3.

The invention is directed to novel and useful means for handling, alining, rotatably supporting, laterally registering and braking web rolls of paper and other material, and for effecting these functions with web rolls of various widths, the web being usually drawn off under tension and also usually at high and varying speeds by the web-con-

suming machine. The invention is further directed to providing such a mechanism which is unusually adequate and efficient for performing all of these functions separately and conjointly, and without causing disturbance or necessity for adjustment of one mechanism by reason of the operation or adjustment of other of the mechanisms or means.

A further object of the invention is to provide such a mechanism which renders unnecessary the ordinary web roll supporting spindle or mandrel, with the necessity of fastening thereto a brake pulley, bringing said pulley into proper relation with the brake mechanism of the press, and later removing the brake pulley from the spindle or mandrel of the exhausted roll. By my invention a web roll is automatically and positively positioned with respect to the mechanism, is quickly operatively mounted 60 in its journal supports, is very quickly and readily brought into lateral registration with the printing press cylinders or other web-using machine, for web rolls of all widths, and is immediately in proper relation with the braking or tension controlling mechanism, and an exhausted roll is removed 65 from the press or other web-using machine with a minimum of time and trouble.

The invention in its entirety comprises 70 means for supporting a fresh web roll which has no spindle but only an axial orifice or tube, and bringing it with certainty to an initial position with respect to the mechanism, and also means are provided for easily 75 lifting the fresh web roll into registry with the supporting spindles. A pair of rotatable spindles are provided for receiving, and engaging in, the ends of the axial orifice of the web roll after it has been moved into 80 alinement therewith, so that the web roll is supported by and rotatable with the spindles. One at least of the spindles is longitudinally movable to clamp the roll and spindles together. The carriers for the spindles are movable toward and from each other, to accommodate rolls of web of various widths.

The supports for these spindles are very accurately axially movable so as to readily 100

and nicely bring a web roll into transverse registry with the plates on a printing press cylinder, or into like relation with any other kind of web-using machine. Braking and 5 tension-controlling means are provided in connection with one of the spindles, to control the paying off of the web in harmony with the varying speed and other requirements and conditions of the printing press 10 or other web-using machine. The removal of the core of an exhausted web roll is effected by a simple movement of one of the supporting spindles.

The foregoing general description, and the 15 following detailed description as well, of a present preferred embodiment of the invention are explanatory and exemplary of the invention, but are not restrictive thereof.

Referring now in detail to the embodiment 20 of the invention illustrated by way of example in the accompanying drawings, the invention is shown applied to a double web roll positioning, hoisting, supporting, registering and controlling mechanism, such as is 25 used on rapid rotary printing presses and elsewhere, and wherein the lead end of a fresh web may be attached to a nearly exhausted web by a "flying paster" or in other manner so as to disturb or retard the web- 30 using machine as little as possible.

In said exemplarily embodied form, the general frame structure comprises vertically-disposed I-beams 1, at either side of the press, and horizontally-disposed I-beams 2 there- 35 above and supported thereby at either side. Bolted to the web of the vertically-disposed I-beam 1 on one side (Figs. 1, 2, 3 and 4) is an upper supporting bracket plate 7, and a corresponding bracket plate 8 is bolted to 40 the corresponding I-beam on the other side. There are likewise a pair of similar or corresponding lower supporting bracket plates, a plate 9 being bolted to the I-beam beneath, the plate 7, and a plate 10 being bolted to 45 the other I-beam beneath the bracket plate 8. These four bracket plates carry the cross supports on which the web roll carrying members are movably and adjustably mounted.

Referring now to the embodied mechanism 50 for supporting and registering one of the web supply rolls, two independently movable frame members, on either of which a web roll engaging, rotatable spindle is journaled, is provided. The frames have a relatively very wide base, which is slidably supported on two fixed supporting and guiding members to give rigidity and precision to the mechanism. As so embodied, a transversely-disposed guide and support in the 55 form of a rod 17 is mounted at either end in apertured bosses 18 and 19, formed respectively on the supporting plates 7 and 8, the rods 17 being held against rotation by suitable means such as a spline 20 within 60 one of the bearing supports. The rod 17 is

longitudinally movable, however, to effect axis-wise or transverse registration of the web roll with respect to the plate cylinders of the press, or with other web-using machine, as will be later more fully described. 70 A second and cooperating transversely-disposed guide and support, shown as a corresponding rod 23, is mounted fixedly in apertured supporting bosses 24 and 25, formed on the upper part of the supporting bracket 75 plates 9 and 10. The rod is held in fixed position by any suitable means, such as clamping screws 26, threaded into the bosses and engaging the rod.

A supporting and spindle-carrying frame 80 member 31, of the general form precedingly described, for one end of the web roll is mounted on the rods 17 and 23, to slide therealong to accommodate web rolls of different widths. This supporting or carrying member has a sleeve 32 mounted on and slidable along the rod 17. The sleeve 32 and all the other corresponding sleeves are relatively very long, and thereby have a long bearing 85 on their supporting and guiding members, such as the rod 17. This cooperates with the wide-apart bearings of the spindle bearing frames on the supports and guides 17 and 23 to give a very firm, rigid and precise bearing and support in all directions. 90

As so embodied, an arm 33 is integral with and extends outwardly and downwardly from the sleeve 32 to, and is fixed to or integral with, a central, cylindrical, axially-apertured bearing hub 34. A sleeve 35, corresponding to sleeve 32, is slidably mounted on shaft 23, and there is an arm 36 integral therewith, extending upwardly and outwardly therefrom, and likewise integral with the journal sleeve or hub 34. This frame, supported and guided by, and slidable along supports 17 and 23, constitutes a rigid support for the spindle which is rotatably journaled in hub 34, and engages one end of the axial orifice of the web roll. I prefer to 100 make the roll-supporting spindle on this side longitudinally stationary, and accordingly a spindle 38 is rotatably mounted in the central aperture of the journal hub or sleeve 105 34. To prevent longitudinal motion of the spindle there is provided a collar 39, fixed to spindle 38 on the inner face of hub 34. At its outer end the spindle projects from hub 34, and a collar 40 is fixed thereon by suitable means such as a pin 41. The spindle 110 is thus rotatable in its journal, but is held against longitudinal movement.

The supporting and journaling means for the other end of the web roll are generally similar, but the web roll-supporting spindle 115 is longitudinally movable, being retractable to receive the web roll therebetween, and then reversely movable to engage the axial orifice and to clamp the web roll between and to the two spindles. The braking or tension- 120

controlling means are also applied to one of the spindles, and preferably but optionally it is applied to this one. In the embodied form, a sleeve 49 is slidably mounted on the shaft 17, and an integral arm 50 extends outwardly and downwardly therefrom, and is integral at its outer end with a journal sleeve or hub 51 for the web roll spindle. A similar and corresponding sleeve 53 is slidably mounted on the rod 23, and has an arm 54 integral therewith and also integral at its outer end with the journal hub 51. The spindle 57 for this end of the web roll is journaled in the hub 51, and the rear end of the spindle projects from the outer end of the hub, and has a final brake pulley carrying portion 58.

The brake pulley 59 is fixed thereon to rotate therewith by suitable means such as a key 60. The brake mechanism may be of any known or other suitable form, and is not shown in full detail. As shown, it comprises arcuate brake shoes 65 and 66, pivoted at 67 and 68, respectively, to brake lever 69 and 70. The brake levers are pivotally mounted to be longitudinally slidable on a supporting rod 71, which rod is fixed to and projects outwardly from the bottom part 73 of the spindle journal hub 51. A suitable tension regulating device 74 for the brake shoe levers is shown. It will be further understood that the particulars of the brake mechanism, and the connections therefrom to an automatic web tension controlling means, may be of any known or other suitable form.

Means are provided for longitudinally moving the spindle 57 in one direction to receive a web roll and thereafter in the opposite direction to force the web roll firmly onto both supporting spindles and thereby to rotatably clamp them together. As embodied (Figs. 1, 3 and 4), an annular groove 77 is formed near the outer end of the spindle 57. A yoked lever 78 is pivotally supported at 79 upon a bracket 80, which is fixed to an extends outwardly from the spindle hub 51. Pins 81 are mounted in the outer ends of the yoked part of the lever 78, and extend into the annular groove 77 in the spindle 57, whereby the lever may move the spindle longitudinally while leaving it free to rotate. Any suitable means may be provided for firmly holding the lever 78 in the web roll clamping position, and in other positions as well. The spindle journal hubs 34 and 51 are likewise relatively very long and furnish an extensive journal bearing for the roll supporting spindles and any side thrust due to the load is correspondingly widely distributed and practically nullified. Furthermore, the spindle journal hubs are connected to the integral supporting frames very close to their inner or load carrying ends, thereby also conducting to the balancing and minimizing of the load strains.

In the embodied form of means for adapting the mechanism to full width or fractional width web rolls, such as three-quarter width, half-width or quarter-width rolls (Figs. 1, 3 and 4), the supporting sleeves 32 and 35, while having a very close fit on their respective supporting rods 17 and 23 are slideable longitudinally thereon. The sleeve 32 is provided with means for clamping it to its rod 17 in any desired longitudinal position, and for this purpose a clamping screw 85 is shown, screw-threaded in the sleeve and engaging the rod. By reason of the integral or fixed structure of this entire carrying frame, the sleeve 35 need not be provided with clamping means but will slide along its rod 23. Similarly, at the other side, the sleeves 49 and 53 likewise have very close fits on the rods 17 and 23, but are longitudinally slideable, and a clamping screw 86 is provided, screw-threaded in the sleeve 49 and engaging rod 17. Thus either or both of the spindle carrying frames are independently slideable on the guiding and supporting members 17 and 23, and therewith all the interconnected mechanisms, to accommodate web rolls of different widths.

Means are provided for effecting accurate axis-wise or lateral registry of the journaled web roll with respect to the printing plates on the press cylinder or the cooperating parts of any other web-using machine. As embodied (Figs. 3, 4 and 7), said means comprise a screw rod 87, screw-threaded into the end of the shaft 17, which shaft it will be recalled is longitudinally slideable in its fixed bearings 18 and 19. At its outer end, screw rod 87 is journaled in an aperture in a bracket 88, which is fixed to and extends outwardly from one of the vertically-disposed side pillars 1 of the frame. On the inner side of its bearing in bracket 88, the screw-rod is provided with a collar 89, pinned to the rod, and on the outer end of the screw-rod a hand wheel 90 is pinned thereto, for the purpose of turning same and in cooperation with the collar 89 to prevent longitudinal movement of the screw-rod in its bearing. Thus, by turning the hand wheel 90, a very accurate and minute longitudinal movement is imparted to the rod 17, and by reason of the sleeves 32 and 49 being fixed thereto, the entire web roll supporting structure, and the web roll therewith, are given a likewise minute and accurate lateral or axis-wise positioning movement.

The mechanism for supporting the other web roll may be similar to, or the same as, that already described, the exhausted web roll being removed from one mechanism, and a full fresh web roll substituted therefor while the web roll on the other mechanism is being run through the press or other web-using machine in the usual and well-known manner. The other web roll mechanism has

supporting means comprising centrally-apertured supporting bosses 99 and 100, formed in the lower parts of the supporting bracket plates 7 and 9. A transversely-disposed supporting and guiding shaft 101 is mounted therein, this shaft corresponding to the shaft 17 on the opposite mechanism. Likewise supporting bosses 102 and 103 are formed respectively in the lower parts of the corresponding supporting bracket plates 8 and 10. A transversely-disposed supporting and guiding shaft 104 is mounted therein, and corresponds to the shaft 23 on the opposite side of the mechanism. The remainder of the mechanism may be the same as that on the opposite side and already described in detail, and need not be described again, the same reference numerals being applied thereto.

20 In accordance with certain features of the invention, means are provided for accurately preliminarily positioning a fresh web supply roll with reference to the herein-before described mechanism, and in conjunction therewith power means for lifting a web roll into alignment with the journal spindles so that by movement of a supporting spindle the web roll may be clamped in feeding or unwinding position. As embodied, (Figs. 1, 2, 3, 5 and 6) a web roll supporting member or hoist 111 is in position beneath the roll-supporting mechanism, and is provided with a concave roll supporting upper face 112. This face 112 is parti-cylindrical and of substantially equal radius with the web roll and is on center both angularly and longitudinally with respect to the web roll carrying spindles. A fresh web roll placed on hoist 111 is therefore centered accurately with respect to the spindles and just below them.

25 In the embodied form of roll hoisting means, guides 113 and 114 are provided at either side of the web roll hoist 111, which center the web roll longitudinally, and the hoist laterally and thereby the web roll angularly. At either side of either end of the support and hoist 111, and fixed to and extending upwardly therefrom, are hooks 115 and 116. A bail or spanner 117 has eyes 118 and 119 at its ends which hook over the hooks 115 and 116, the bail projecting upwardly and being provided with a spacing and reinforcing cross brace 120. Fixed to the upper end of the bail 117 (Figs. 1, 2 and 5) is a cable 122, which is wound on a drum 123, fixed on a shaft 124, the shaft 124 being journaled in supporting brackets 125, 126 and 127, fixed to the frame structure. A collar 128 is fixed on the shaft 124 at one side of the journal bearing 126 to prevent longitudinal movement of the shaft in one direction. At the opposite end of the web roll support and hoist, similar mechanism to that already described is provided, which 30 need not be described again, the same refer-

ence numerals being applied thereto. The cable 122' of this mechanism is wound about a drum 135 fixed to the shaft 124 so that both ends of the web hoist will be raised together.

35 The embodied form of power driven means for raising and lowering the web roll hoists is common to both web-roll mechanisms and operates them alternatively by means of clutch mechanisms. As embodied, it comprises a worm-wheel or other suitable gear wheel 136, fixed to the outer end of the shaft 124 to rotate therewith, the hub thereof abutting on the journal bearing 125 and preventing longitudinal motion of the shaft 124 in the opposite direction. In mesh with the gear wheel 136 of one of the web roll hoists is a worm or one tooth gear, or other corresponding mechanism 137, which is sleeved loosely on a shaft 138, and a clutch jaw 139 is likewise fixed to the sleeve of the gear wheel. Shaft 138 is journaled in a series of brackets 140 carried by the top frame of the machine. Mounted on shaft 138 to rotate therewith, but to be slidable therealong, is a clutch jaw 141, which is movable into and out of engaging relation with the clutch jaw 139 of the gear 137. For the purpose of moving this clutch jaw into and out of engagement, the hub thereof is provided with an annular groove 143, which is embraced by a yoke lever 144, having pins projecting into the groove 143. Lever 144 is pivotally supported at 145 on the machine frame, and has fixed thereto a hand lever 146. Fixed on shaft 138 is a gear wheel 147, which meshes with a pinion 148 fixed on the shaft 149 of a motor 150, supported on the machine frame.

40 On the opposite side a worm wheel, or one-tooth gear, or other suitable gear wheel 157 is sleeved loosely on shaft 138, and has a clutch jaw 158 likewise fixed to said sleeve. A cooperating clutch jaw 159 is rotatable with, but slideable along shaft 138 into and out of engagement with the clutch jaw 158 to rotate the gear 157 or to permit it to remain idle. The actuating mechanism for the clutch jaw 159 is similar to that for clutch jaw 141 for the hoist on the opposite side and need not be described in further detail. This mechanism is provided with a similar clutch shifting handle 160.

45 The manner of operation of the various parts of the mechanism has been described in detail herein before, and may be summarized as follows:

50 A fresh web supply roll is delivered to the roll hoist 111, and is automatically positioned thereon with respect to the roll-supporting spindles by the parti-cylindrical top face 112, the hoist and roll being maintained in proper position and alignment by the guides 113 and 114, while being free to move upwardly and downwardly. The sleeves 32 55

and 49 are moved along the supporting rod 117 in either direction to correspond to the width of a full width roll or a part-width roll, and in the case of the latter, to correspond also to the manner of its feed into the press. That is, with respect to the length of the press cylinder; that is, a three-quarter width web might feed two sheets to either side of the slitter and one to the other, and a half-width roll might be led to the former, or it might be slit and a half-width led to either former, or any other desired relation might be effected.

By means of the clutch-operating hand lever 146 or 160, either clutch may be thrown in, and the corresponding hoist 111 raised until the axial orifice of the roll is in alignment with the roll-supporting spindles 38 and 57. The spindle 57 has been previously withdrawn by means of the hand lever 78, and after the web roll is in axial alignment, the lever 78 is moved to force both spindles 38 and 57 tightly into either end of the axial orifice of the web roll, the spindles thereby firmly frictionally engaging the web roll, the roll and the spindles thereafter rotating together.

The brake pulley and brake are in permanent relation with respect to the spindle 57, and move therewith, sliding along the rod 71. Suitable connections to provide for lateral movement of connections from the brake mechanism to automatic tension mechanism may be provided of any suitable form, such, for example, as is shown in copending application, Ser. No. 302,460, filed August 28, 1928. The accurate lateral or axis-wise registration of the web with the printing plates or other corresponding instrumentalities is effected by the hand-wheel 90 and cooperating mechanism, as already described. After a web roll is exhausted, the central tube or waste portion may be removed merely by moving the lever 78 and withdrawing the spindle 67, and without disturbing the relations or the mechanism of the brake and its control.

The invention in its broader aspects is not limited to the specific mechanisms shown and described but departures may be made therefrom within the scope of the accompanying claims without departing from the principles of the invention and without sacrificing its chief advantages.

What I claim is:—

1. A web roll mechanism including in combination a plurality of vertically and transversely disposed supports, a pair of carriers, each movably mounted upon said supports and extending laterally therefrom, and devices mounted on said carriers for engaging either end of the axial orifice of a web roll.

2. A web roll mechanism including in combination a plurality of vertically and transversely disposed supports, a pair of carriers,

each separately movably mounted upon said supports and extending laterally therefrom, and devices mounted on said carriers for engaging either end of the axial orifice of a web roll.

3. A web roll mechanism including in combination a plurality of vertically and transversely disposed supports, a pair of carriers, each movably mounted upon said supports and extending laterally therefrom, devices mounted on said carriers for engaging either end of the axial orifice of a web roll and means for moving a web roll into approximate alignment with said engaging devices.

4. A web roll mechanism including in combination a plurality of vertically and transversely disposed supports, a pair of carriers, each separately movably mounted upon said supports and extending laterally therefrom, devices mounted on said carriers for engaging either end of the axial orifice of a web roll and means for fastening said carriers respectively in position on one of said supports.

5. A web roll mechanism including in combination a plurality of pairs of transversely disposed supports located closely contiguous to each other, a pair of web roll carriers mounted for transverse movement on one pair of supports, and a pair of web roll carriers mounted for transverse movement on the other pair of supports and extending in a different direction from said first pair of web roll carriers.

6. A web roll mechanism including in combination a plurality of pairs of vertically and transversely disposed supports located in approximately a vertical plane, a pair of web roll carriers movably mounted on one pair of supports and extending transversely therefrom, and a pair of web roll carriers movably mounted on the other pair of said supports and extending transversely therefrom in the opposite direction.

7. A web roll mechanism including in combination a pair of supporting devices for engaging either end of the axial orifice of a web roll, another pair of supporting devices for engaging either end of the axial orifice of a web roll, carrying means for one pair of web roll supporting devices, carrying means for the other pair of web roll supporting devices, a common support for said two carrying means, the carrying means being independently movable on said support to accommodate them to web rolls of different widths.

8. A web roll mechanism including in combination a pair of supporting devices for engaging either end of the axial orifice of a web roll, another pair of supporting devices for engaging either end of the axial orifice of a web roll, carrying means for one pair of web roll supporting devices, carrying means for the other pair of web roll supporting devices, a common support for said two carrying

means, and means for minutely moving either carrying means axially independently of the other to register its web roll relatively to the web using machine.

5 In testimony whereof, I have signed my name to this specification.

HUBERT LANG.
